UNITED STATES PATENT OFFICE.

THEODORE N. STRAND, OF LOS ANGELES, CALIFORNIA.

DESIGN FOR A CHAIR.

Application filed June 6, 1927. Serial No. 22,337. Term of patent 14 years.

To all whom it may concern:

Be it known that I, THEODORE N. STRAND, a citizen of the United States, residing at Los Angeles, in the county of Los Angeles and State of California, have invented a new, original, and ornamental Design for Chair, of which the following is a specification, reference being had to the accompanying drawing, forming part hereof.

In the drawing, the figure is a perspective view of the chair, showing my new design.

I claim:

The ornamental design for a chair, as shown.

THEODORE N. STRAND.
